J. G. WALLMANN

ELECTRIC HEATING UNIT

Filed April 10, 1922

UNITED STATES PATENT OFFICE.

JOHANN G. WALLMANN, OF OAKLAND, CALIFORNIA.

ELECTRIC HEATING UNIT.

Application filed April 10, 1922. Serial No. 550,993.

To all whom it may concern:

Be it known that I, JOHANN G. WALLMANN, a citizen of the United States, residing at Oakland, in the county of Alameda 5 and State of California, have invented certain new and useful Improvements in Electric Heating Units, of which the following is a specification.

My invention is an improved electric heating element, particularly suitable for bake ovens, driers, and other heating devices, constructed with novel controlling means whereby the use of portable cord plugs which get out of order very easily, are eliminated.

Referring to the annexed drawing in which my invention is illustrated and which forms a part of this specification:

Figure 1 is a side view of my electric heating element in circuit closing position mounted in the lower part of an oven which is shown in vertical section.

Figure 2 is a plan view of my heating element.

Figure 3 is a fragmentary side view partly in section of my electric heating element in open circuit position.

Figure 4 is a detail view in section along line 4—4 of Fig. 2 showing the insulating saddles and the mounts therefor.

In the drawing 1 indicates a drawer in the form of a rectangular frame which slides in the lower part of a heating device 2 such as a bake oven, drier and the like through an opening 3 in said heating device. Rods 4 and 5 extend transversely of the frame 1 and are secured at their ends in the side walls of the frame, the rod 4 being located toward the outer end of the frame and the rod 5 being located near the inner end of the frame. On the outer end wall of the frame 1 is secured a plate 6 of larger area than the said outer end wall which plate engages the outside of the wall of the heating device 2 and limits the inward movement of the drawer 1 in its circuit closing and heating position as shown in Figure 1. Angle iron 7 is secured to one side of the drawer 1 which engages the wall of the heating device 2 and limits the outward movement of the drawer 1 which is a short movement. A wall of insulation 8 extends transversely of the drawer 1 between the forward end thereof and the rod 4. A brass expansion bracket 9 extends transversely of the frame 1 from one side wall thereof and has an eye 10 at one end adjacent said side wall through which extends the rod 4. Nuts 11—11 screw on said rod against the inside of the side walls of the frame 1 to hold the rod in the frame. Nuts 12 and 13 also screw on the rod 4 against the sides respectively of the eye 10 and hold the bracket 9 rigidly on said rod. A brass expansion bracket 14 extends transversely of the frame 1 from the other side wall thereof and has an eye 15 at its end adjacent said side wall through which eye loosely extends the rod 4 whereby the bracket is slidably mounted on said rod. An iron tie plate 16 is interposed between the brackets 9 and 14 and said brackets and plate are all riveted together by rivets 17. Nuts 18—18 screw on the rod 5 against the inside of the side walls of the frame 1 and hold the rod in place in the frame. A brass expansion bracket 19 extends transversely of the frame 1 from one side wall thereof and has an eye 20 at its end adjacent said wall through which extends the rod 5. Nuts 21 and 22 screw on said rod against the respective sides of said eye whereby the bracket is held rigidly on said rod. A brass bracket 23 extends transversely of the drawer 1 from the other side thereof and has an eye 24 adjacent said side through which eye loosely extends the rod 5 whereby said bracket is loosely mounted to slide on said rod. An iron tie plate 25 is interposed between the brackets 19 and 23 and said brackets and tie plate are all secured together by rivets 26. An iron bar 27 is secured at its ends to the outer end of the brackets 9 and 19 and an asbestos composition insulating saddle 28 fits over the outer edge of the bar 27, said saddle having a plurality of longitudinally spaced notches 29 in its outer edge. An iron bar 30 is secured at its ends to the outer ends of the brackets 14 and 23 and a fibre insulating saddle 31 fits over the outer edge of the bar 30, said saddle having a plurality of longitudinally spaced notches 32 in its outer edge. A fine coil of wire 33 is coiled around the saddles 28 and 31 in the notches 29 and 32 and secured to screw terminals 34 and 35 at opposite ends of the saddle 28. A wire 36 is connected at one end to terminal 34 and at its other end to a terminal 37 on the wall 8. A wire 38 is connected at one end to terminal 35 and at its other end to a terminal 39 on the wall 8. A hollow handle 40 is secured at its upper end to the plate 6 in communication with apertures

41 and 42 in said plate and in the outer end wall of the drawer 1.

My heating element is controlled by an electric switch 45 which comprises a pair of 5 sockets 46 and 47 and a pair of plugs 48 and 49, said sockets being mounted in a switch wire box 50 secured to the under side of the heating device 2 at the front thereof, and said plugs being mounted on the lower 10 end of said handle 40. A wire 51 extends through the handle 40 and is connected at one end to terminal 39 and at its other end to plug 48. A wire 52 extends through the handle 40 and is connected at one end to terminal 37 and at its other end to plug 49. Wires 53 and 54 are connected respectively 15 to sockets 46 and 47 in box 50 and extend through said box and are connected to a source of electric power (not shown).

20 To close the circuit including my heating element the drawer 1 is pushed all the way into the heating device 2 until the plate 6 engages the wall of said device in which position the plugs 48 and 49 are introduced in- 25 to the sockets 46 and 47 respectively, closing the switch 45. Current passes from the switch through wire 51, terminal 39, wire 38, terminal 35, coil 33, terminal 34, wire 36, terminal 37, and wire 52 back to the switch, 30 the current heating the coil 33 which generates heat in the heating device 2. The coefficient of expansion of the brass brackets 9, 14, 19 and 23 being greater than that of the coil 33, the bar 30 and saddle 31 are 35 moved away from the bar 27 and saddle 28

to such an extent as to take up the slack in said coil and maintain said coil taut so that the individual coils thereof cannot come together and short circuit my heating element.

The heating circuit is broken by pulling 40 out the drawer 1 and disengaging the plugs 48 and 49 from the sockets 46 and 47, in which position the heat in the heating device 2 escapes through the forward part of the 45 drawer 1 and through the opening 3.

Having described my invention, I claim:

1. In a heating element relatively movable insulating saddles, supports therefor, a coil wound around said saddles and means comprising a member adapted to expand under 50 heat to produce relative movement of said saddles, one end of said member being fixed to a support and the other end of said member being slidably mounted on said support.

2. In a heating element, a drawer, a pair of rods extending transversely of said drawer, brass brackets fixed on said rods respectively, brass brackets slideable on said rods respectively, an iron tie plate between each pair of fixed and slideable brackets to 60 which plate said brackets are secured, a bar secured at its ends to said fixed brackets respectively, an insulating saddle fitted on said bar, a bar secured at its ends to said slideable brackets, an insulating saddle fitted on said 65 latter bar, and a coil of fine wire wound around said saddles.

In testimony whereof I affix my signature.

JOHANN G. WALLMANN.
